UNITED STATES PATENT OFFICE.

WILLIAM HAGENBERG, OF TOLEDO, OHIO.

DUST-ARRESTER.

SPECIFICATION forming part of Letters Patent No. 333,217, dated December 29, 1885.

Application filed June 24, 1885. Serial No. 169,667. (No model.)

To all whom it may concern:

Be it known that I, WILLIAM HAGENBERG, a citizen of the United States, residing at Toledo, in the county of Lucas and State of Ohio, have invented a new and useful Improvement 5 in Dust-Arresters, of which the following is a specification.

My invention relates to improvements in "storage and dust-arresting structures," so called, the necessity for which exists in manufactories—such as planing-mills, cotton-mills, sawing-mills, &c., which have quantities of material, refuse or otherwise, to be carried from place to place or removed from the premises 10 or to storing-receptacles for fuel, and which commonly contain quantites of fine dust, the said materials usually being conveyed through tubes or pipes by currents of air, put in motion by exhausting-fans; and while the 15 coarser and heavier parts of the said materials are easily deposited in the desired place or receptacle by a careful adjustment of the forces of the air-blast and gravitation, it is found that when this end is best attained an almost 20 insurmountable difficulty arises in separating from the conveying air-blast the light powdery dust contained in the said material being conveyed, which, instead of precipitating with the heavier materials, is carried away 25 by the escaping air out of the containing building or apartments into the open atmosphere, and, depositing upon buildings, lumber-piles, alleys, streets, and neighboring property, becomes a source of many inconveniences and dangers, among which may be 30 mentioned a very large increase of fire risk. By every system and device employing an air-blast for removing said refuse material and having connected therewith a dust-arrester 35 composed of and using "burlaps" or openly-woven fabrics as a separator of the dust and air, by passing through said fabrics with an ascending motion and discharged at the same or at a greater altitude than which it enters 40 the said fabrics, in such cases, almost without an exception, the air is discharged into the open atmosphere through a lattice-work placed upon the roof of the building, and said lattice is usually, for economic purposes, made 45 of wood, but if made of iron it is but little better for being of an open nature, and the whole internal construction of the dust-ar-

rester being made of and at all times thoroughly impregnated with highly-combustible materials, among which are the burlaps, wooden frames, &c., and the excessively-fine and almost explosive dust which it is the object of the mechanism to remove. It will therefore be seen that any mechanism of such a nature which has for its object the removal of said 60 dust by means of an air-blast, as hereinbefore named, and discharging at or above the top of the building, either openly or through a lattice-work, or in any known way, is an inflammable and highly-dangerous attachment 65 to a building.

The nature of my invention consists in so constructing and operating the necessary and most approved appliances known in the arts for removing said dust, and in such a way as 70 that the danger from fire, which is of paramount importance, shall as far as possible be removed. A second and very important object to be gained is the utilization of the air 75 of the blast for other purposes after it has been freed from the dust, as will be hereinafter named and described, which air in the old methods of construction is so far removed from any accessible point before it parts with its dust that its further use is practically beyond accomplishment. I attain these objects by the mechanism illustrated in the accompanying drawings, in which—

Figure 1 is a perspective view of a building containing my improvement, and said building 85 is applied as an annex to a manufactory where it is desired to use this apparatus; but the said building may be constructed as a part of any suitable building, or, if thought best, it may be a separate structure, and entirely isolated 90 from the manufactory for which it is operated. Fig. 2 is an enlarged view of one of the dust-arresters shown at A, Fig. 1, and is cut away through its central part, so as to exhibit only its ends. Fig. 3 illustrates another 95 form of dust-arrester, which may be used instead of that shown in Fig. 2, and shows only the top end, the lower end being similar to the form shown in Fig. 2. Fig. 4 is a section of one of the dust-arresters A on line B, 100 Fig. 2. Fig. 5 is a section of the dust-arrester shown in Fig. 3, taken on line C, same figure.

Similar letter refer to similar parts throughout the several views.

Returning to Fig. 1, it will be seen that this illustration represents the building as being open on the side D, toward which we are now looking. This is for the purpose of showing 5 the internal construction of the same; but when in use this side is closed, like the other three vertical sides.

E E are two vaults or compartments, and in this description we will assume that the apparatus 10 is being applied to a lumber-working or planing mill. Into the vaults E E, at a point below the lattice H, the shavings are conducted through a pipe, F, by means of an air-blast in a well-known manner, one of the 15 vaults only being filled at a time, while the other is being drawn from through the hatchways G, which may be opened by any approved method, such as a sliding or swinging gate. The tops of these vaults are partially 20 covered, to assist in retaining the incoming materials, with slats H, having openings between them which are about equal in width to the width of the slats. The air, being the carrying-vehicle of the shavings, necessarily 25 passes with the shavings into the vaults E below the level of the lattice H, and must have an outlet or escape, which it finds between the slats H, carrying with it the fine particles of wood and other dust which will not settle with 30 the shavings. The removal of this dust from the escaping air by a practically fire-proof mechanism, as before stated, is the primary object of my invention. This is accomplished in the compartment I.

35 The compartment I contains a suitable number of dust-arresters, preferably opening through and attached to the partition J, one of which is shown in Fig. 2, and is constructed as follows: It has a top and lower case, K, 40 and corner-supports L. (Shown in Fig. 4.) To these parts are secured, with tacks or otherwise, "burlaps," so called, or any good open fibrous fabric, N, Fig. 2, and to the lower end of each of these dust-arresters is attached a 45 door, R, or means of closing the same when in operation, the objects of the said doors being to hold the collecting dust until discharged upon the floor S or into any suitable removing-conveyer. The air in passing from the vaults 50 E, as before named, takes the directions of the arrows M, and passing down the tubes or dust-arresters A the particles of dust are retained in the meshes of the fabric N, while the air passes freely through into the compartment I, and from this compartment I it may be conducted 55 into the open atmosphere through a lattice, O, or any other suitable outlet, and in very exposed places—such as in thickly-built cities where the fire danger is great—an extra stack or chimney, T, may be constructed for conveying the said air away, not because of there being any combustible materials still remaining in the air, but for the purpose of removing the said outlet as far as may be from 60 the combustible material within the building and from the danger of contact with fire without. The said stack is also a help to the

70 draft. After the air-blast has passed through the meshes of the fabric, being now in an accessible locality, it may be conducted away in tubes, to be used for ventilating or cooling purposes, or for draft and combustion uses in heating and steam-generating, &c., and the pressure may at all times be regulated by an adjusting mechanism connected with the lattice O or by means of chimney-dampers, when desired to be used for ventilating and cooling purposes, or for draft and combustion in making steam, &c.

75 Any suitable valve or gate may be applied in the pipe F, that the attendant may regulate the admission into either of the vaults at pleasure.

I do not confine myself to the form of dust-arrester shown in Fig. 2, for one of equal 80 value and utility may be constructed, as shown in Fig. 3, wherein the open fabric N is applied upon only two sides, P and Q, the operation and results being identical. When this plan is carried out, as herein shown and described, 85 it is obvious that the whole apparatus is practically fire-proof, and that the escaping air can, in a large measure, be utilized.

I am aware that prior to my invention storage and dust-arresting structures of various forms have been known and used, most of 90 which are operated by means of an air-blast, in connection with openly-meshed fabrics for arresting the dust; but in every instance known to me these elements are used in combination with outlets near or upon the top of the roof of the containing-building. I do not therefore claim such a combination, broadly. 95

100 What I claim as my invention, and desire to secure by Letters Patent, is—

105 1. In a storage and dust-arresting structure having one or more air and material conveyors, F, discharging into the vault or vaults E E, the dust-arresting compartment I, adjoining or interposed between said vaults, when the said compartment I is provided with downwardly-discharging dust-arresting tubes A, which open at or near their upper extremity for the reception of dust and the air conveying the same in their passage from the 110 vault or vaults E E, substantially as shown and described.

115 2. In a storage and dust-arresting structure having one or more air and material conveyors, F, discharging into the vault or vaults E E, and having the dust-arresting compartment I adjoining or interposed between said vaults, the perforated top covering, J, of the dust-arresting compartment I, when the said perforations open to and connect with the 120 downwardly-discharging dust-arresting tubes A, substantially as shown and described.

125 3. In a storage and dust-arresting structure, the combination of the conveyer or conveyers F F, the vault or vaults E E, dust-arresting compartment I, adjoining or interposed between said vaults, with its tubes A, when said tubes A have opening and closing outlets at their lower extremities for regulating the dis-

charge of dust, and on their vertical sides open-meshed fabric for the discharge of air, substantially as shown and described.

4. In a storage and dust-arresting structure having the conveyer or conveyers F F and vault or vaults E E, the downwardly-discharging dust-arresters A, located in compartment I, in combination with stack T, substantially as shown and described.

10 5. In a storage and dust-arresting structure

having the conveyer or conveyers F F and the vault or vaults E E, through which the dust-conveying current is passed, the slatted floor H, located in the upper part of the vault or vaults E E, arresting the coarser refuse 15 matter, substantially as shown and described.

WILLIAM HAGENBERG.
